UNITED STATES PATENT OFFICE.

CHARLES W. BOLGIANO, OF WASHINGTON, DISTRICT OF COLUMBIA.

PACKAGE-SEALING MACHINE.

Application filed September 20, 1928. Serial No. 136,617.

This invention relates to certain new and useful improvements in the construction and operation of package sealing machines.

The invention is concerned, more particularly, with the provision of an automatic machine capable of facilitating the sealing of envelopes and similar containers of the type commonly employed for packaging seeds and like commodities.

10 An object of the invention is to provide a compact type of automatic sealing machine having the various elements thereof including the prime mover mounted upon a common portable support capable of being readily transferred from place to place as circumstances may require.

Another object of the invention is to provide a package sealing machine having provision for automatically applying adhesive to the open flap of a package, automatically folding the flap down upon the body of the package subsequent to the application of adhesive and for applying heat and pressure to the folded flap to cause the latter to adhere firmly to the body of the package.

A further object of the invention is to provide a novel type of package conveyor which is adjustable to accommodate packages of varying thicknesses.

30 A still further object of the invention is to provide a novel combination of adhesive applier and conveyor in which the adhesive applier is operated by a movable element of the conveyor.

35 A still further object of the invention is to provide a novel combination of elements in which a single power driven conveyor serves to deliver the packages to the adhesive applier, folder, and heat and pressure applying means in the order named besides serving to effect positive operation of the adhesive applier.

40 Other objects and advantages of the invention as well as the details of construction, combination and arrangement of parts characterizing the embodiment herein disclosed will be more readily apparent from the following detailed description taken in connection with the accompanying drawings 45 in which:

Figure 1 is a top plan view of the complete machine.

Figure 2 is a front elevational view of the machine with the adhesive applier appearing in perspective.

55 Figure 3 is a vertical sectional view through the tank of the adhesive applier, certain shafts and other operating elements being shown in elevation.

Figure 4 is a fragmentary view in side elevation of the conveyor, folder and heat and pressure applying means.

Figure 5 is a detailed view partly in section and partly in plan of an adjusting device for regulating the conveyor to accommodate packages of varying width and,

65 Figure 6 is a transverse sectional view taken along the line 6—6 of Figure 1.

The invention, as herein described in detail, consists of an adhesive applier for applying adhesive to the open flap of a package, a folder for folding the flap down upon the body of the package subsequent to the application of adhesive, a pressure applier for pressing the folded flap firmly against the body of the package, a heat applier for applying heat to the folded flap practically simultaneously with the application of pressure and a conveyor serving to deliver the packages to the aforesaid elements and to otherwise cooperate therewith.

70 For convenience of description it is deemed expedient to describe the main elements of the complete combination in the order of their operation beginning with the conveyor.

The conveyor.

75 A relatively large wheel 5 and an endless drive belt 6 constitute the two main elements of the package conveyor. The wheel is mounted to rotate freely about a vertical shaft 7 having an enlarged lower end 8 forming a sustaining base which is secured, by bolts 9 or equivalent fastenings, to the top 10 of a portable table having the usual arrangement of supporting legs. The drive belt travels, in contact with the wheel, from point A to point B (see Figure 1) and is driven to move in the direction indicated 80

85 90 95 100

by the arrow. From point B the belt passes around a horizontal pulley 11 and from thence rearwardly across the table top to a vertical pulley 12. As it leaves the last mentioned pulley the belt passes downwardly through a slot 13 and around the underside of a drive pulley 14 fixed to a shaft 15 journalled between spaced standard 16' depending from the underside of the table top 10. From drive pulley 14 the belt is carried upwardly over a tension pulley 16' carried at the upper end of a swinging hanger 17 having its lower end pivoted upon shaft 15. At an intermediate point hanger 17 is connected to standards 16 by a spring 18 which causes pulley 16 to maintain proper tension upon the belt. From the tension pulley 16' the belt passes upwardly around a further guide pulley 19 and through a second slot 20 (see Figure 1) formed in the table top 10. From the slot 20 the belt passes over a vertical pulley 21 and forwardly across the table top to a horizontal pulley 22 corresponding to the pulley 11 and located adjacent the aforementioned point A.

In the operation of the conveyor it will be understood that the packages are interposed between the belt and the wheel at the point 30 A and are caused to travel with and between these elements to the point B. The conveyor is adaptable to packages of varying thicknesses by regulating the tension in that portion of the belt traveling around the wheel 5 and, to this end, the aforesaid pulley 22 is fixed to a freely rotatable and laterally movable shaft 23 having its lower end journalled in a plate 24 having one end pivoted as at 25 to the table top 10. At its other end the plate is provided with a depending flange 25' through which is threaded an adjusting screw 26 having its terminal portions mounted to rotate in the flanges 27 of a plate 28 suitably secured to the table. Any suitable expedient may be resorted to for holding the adjusting screw against longitudinal movement with reference to its supporting flanges such as the arrangement indicated at 29 in Figure 5. It is thus apparent that as the screw is operated the plate 24 together with the shaft 23 and pulley 22 will be shifted to or from the wheel 5 thus varying the tension in that portion of the belt passing around the wheel and adjusting the conveyor to accommodate packages of varying thickness.

Adjacent to the point A a suitable platform 30 is mounted upon which the packages are placed in upright position preparatory to being moved into contact with the wheel and belt at the said point A. Vertical adjustment of the platform to suit different conditions is provided for by a slot and pin connection 31 as shown to advantage in Figure 2.

The shaft 15, which carries the belt drive pulley 14, is provided with a relatively large fixed sheave 32 driven by belt 32' from the relatively small sheave 33 of an electric motor 33'. This motor may be provided with any suitable form of control and, as will be well understood, the relative ratio of the sheave 32 and 33 will depend upon the speed found suitable for the conveyor.

The adhesive applier.

As each package is gripped by the conveyor at the point A adhesive is applied to the open flap of the package from the rim of a rolling contact device or wheel 34 which is mounted upon the upper end of a shaft 35 journalled in bearings 36 (see Figure 3) carried by the tank 37 of the adhesive applier. Between the bearings 36 shaft 35 is equipped with a fixed pulley 38 connected by belt 39 to a pulley 40 on the shaft 23 which carries the drive belt adjusting pulley 22. From this description it is apparent that the rolling contact device or wheel 34 is operated directly by the conveyor belt 6. Immediately below wheel 34 shaft 35 is equipped with a pinion 41 meshing with a pinion 42 fixed to one end of a shaft 43 passing through the side walls of the aforesaid adhesive tank 47. Fixed to shaft 43, within said tank, is a vertical disc 44 serving to transfer adhesive from the tank to the rim of wheel 34. Through the medium of pinions 41 and 42 disc 44 is driven in an anti-clockwise direction as viewed from the right in Figure 3 and surplus adhesive carried upwardly by the disc is caused to return to the tank by a scraper 45 fixed to the upper edge of the tank and having portions extending upon opposite sides of the disc. In order to prevent dripping of surplus adhesive supplied to the wheel 34 I prefer to mount within the tank 37 a brush 46 which engages the lower outer edge portion of wheel 34 and causes surplus moisture to drip from the wheel into the tank.

The folder.

From the adhesive applier above described each package is carried by the conveyor to a folder 48 which functions to fold the flap down upon the body of the package. This folder consists of a metal plate made U-shape for the greater portion of its length to straddle the rim of wheel 5. At the receiving end of the folder the outer side and bight portion of the plate are shaped in the peculiar manner indicated at 49 in Figure 4 so that the folding of the flap is accomplished in a gradual manner as is common with folding devices of this character. The folder is supported in operative position by suitable standards 50 having their upper ends suitably fastened to the folder and their lower ends anchored to the table top 10.

The pressure and heat applying means.

From the folder 48 each package is delivered to the pressure and heat applying means which consists of a curved and relatively narrow pressure strip 52 passing around the wheel 5 from point C to point D with the terminals of the strip flared outwardly from the wheel. Fastened to the outer side of this pressure strip are a pair of spaced electric heating plates 53 having terminals 54 to which the conductors 55 are connected as shown in Figure 1 or in any other suitable manner. The pressure strip and heating plates are secured to and supported by a plurality of standards 56 having their lower ends hinged to the table top as indicated at 57. Pressure springs 58 bearing against the outer sides of these standards serve to press the latter inwardly and thereby hold the pressure strip in yielding engagement with the wheel 5. In practice the flap-closed portions of the packages are caused to travel between the strip 52 and the wheel whereby the flaps are pressed firmly to the bodies of the packages while the heat radiating from plates 53 serves to dry the applied adhesive. The packages are automatically released from the conveyor at or about the point B and are permitted to drop into any suitable receiver provided for this purpose.

It is thought that the complete operation of the machine will be clear from the foregoing description and it will be understood that various changes in the construction, combination and arrangement of the various elements may be resorted to within the scope of the appended claims without departing from the spirit of the invention.

What I claim:

1. A package sealing machine comprising means for applying adhesive to the open flap of a package, means for folding the flap down upon the body of the package subsequent to the application of adhesive and a pivotally mounted spring pressed band for applying pressure to the folded flap to cause the flap to adhere firmly to the body of the package.

2. A package sealing machine comprising means for applying adhesive to the open flap of a package, means for folding the flap down upon the body of the package subsequent to the application of adhesive and an electrically heated spring pressed band arranged to apply heat and pressure to the folded flap.

3. A package sealing machine comprising an adhesive applier for applying adhesive to the open flap of a package, a folder for folding the flap down upon the body of the package subsequent to the application of adhesive, an automatic conveyor functioning to support the packages in upright position

and to deliver said packages first to the adhesive applier and then to the folder, a pressure applying band arranged to engage the flaps of the packages subsequent to the folding operation and electrically heated plates 70 carried by said band.

4. A package sealing machine comprising a conveyor serving to grip and support the packages and to cause the same to travel in a predetermined path while maintaining 75 said packages in upright position, an adhesive applier to which the packages are initially delivered by the conveyor whereby adhesive is applied to the open flap of the packages, a folder to which the packages are carried by the conveyor subsequent to the application of adhesive, said folder serving to fold the flaps down upon the body of the packages, a pivotally mounted spring 80 pressed pressure applying band to which the flaps are delivered by the conveyor after the folding operation, and means for heating 85 said band.

5. A package sealing machine comprising a conveyor including a rotatably mounted wheel and a drive belt trained around a portion of said wheel, said wheel and belt being adapted to receive and carry the packages therebetween, means for applying adhesive to the open flaps of said packages and 90 a folder including a U-shaped blade straddling one rim edge of the wheel with the entrance end of the folder shaped to effect a gradual down turning of the flap as each package passes therethrough. 100

6. In a package sealing machine, the provision of means for applying pressure to the flaps of the packages subsequent to the adhesive coating and folding of said flaps, said means comprising a pressure applying band 95 beneath which the closed flaps of the packages are caused to travel, a plurality of hingedly mounted standards carrying said band and pressure applying springs engaging said standards and serving to press the 105 band toward the packages.

7. A package closing and sealing machine comprising a relatively large rotatably mounted wheel, an endless belt arranged to travel in contact with a substantial portion 110 of the periphery of said wheel and forming therewith a package conveyor, the upper edge of said belt being located inwardly of one edge of the wheel to enable the packages to be carried between the belt and wheel 115 with the flap portions of the packages projected upwardly beyond the upper edge of the belt, an adhesive applier arranged in proximity to the initial point of contact between the wheel and the belt so as to apply 120 adhesive to the open flaps of the packages during the early movement thereof between the wheel and the belt, a flap folding plate mounted in proximity to the adhesive applier and between the latter and the point 125 130

where the bolt leaves the wheel, a curved pressure applying plate extending around the wheel from the flap folding plate to a point in proximity to where the belt leaves the wheel and arranged above the upper edge of the belt so as to directly engage the folded flaps of the packages as the latter leave the folding plate and means for resiliently pressing said plate toward the wheel. In testimony whereof I hereunto affix my signature.

CHARLES W. BOLGIANO.
